CLAIM

The ornamental design for a presenter device as shown and described.

DESCRIPTION

FIG. 1 is a top, front perspective view of a presenter device showing our new design;

FIG. 2 is a top, rear perspective view thereof;

FIG. 3 is a bottom perspective view thereof;

FIG. 4 is a front plan view thereof;

FIG. 5 is a rear plan view thereof;

FIG. 6 is a left-side elevation view thereof;

FIG. 7 is a right-side elevation view thereof;

FIG. 8 is a top plan view thereof; and,

FIG. 9 is a bottom plan view thereof.

The broken lines depict portions of the presenter device in which the design is embodied that form no part of the claimed design.
